UNITED STATES PATENT OFFICE.

WALTER E. CLAUSSEN, OF HARTFORD, CONNECTICUT.

FEEDING MECHANISM.

1,086,701.

Specification of Letters Patent.

Patented Feb. 10, 1914.

Application filed June 12, 1912. Serial No. 703,196.

To all whom it may concern:

Be it known that I, WALTER E. CLAUSSEN, a citizen of the United States, residing at Hartford, in the county of Hartford and 5 State of Connecticut, have invented certain new and useful Improvements in Feeding Mechanism, of which the following is a specification.

This invention relates to feeding mechanism, and the same may be employed with advantage in many different connections or as part of machines of various types; it is of especial utility, however, when incorporated in or constituting a portion of a machine for making paper cups, and in this particular use is adapted to supply blanks one at a time from a pile or stack to cup-forming mechanism of any desirable nature.

20 Among the objects of the invention are the provision of mechanism of the character noted, which is simply in construction, effective in action, and by which blanks can be accurately and rapidly furnished to any 25 part designed to operate upon the same.

The invention possesses other features of novelty and advantage, which with the foregoing will be outlined at length in the following description, wherein I will set forth 30 in detail that one of the several forms of embodiment of the invention which I have selected for illustration in the drawings accompanying and forming part of the present specification, this disclosure being primarily 35 provided to enable those skilled in the art to practise the same. It will be understood therefore that I do not restrict myself to such disclosure; I may depart therefrom in several respects within the scope of my invention defined by the claims following said 40 description.

Referring to said drawings: Figure 1 is a top plan view of feeding mechanism involving my invention. Fig. 2 is a side elevation 45 of the same partly in section. Fig. 3 is a cross section on the line 3—3 of Fig. 2 looking in the direction of the arrow. Fig. 4 is a front elevation. Fig. 5 is a transverse section on the line 5—5 of Fig. 2. Fig. 6 is a 50 section on the line 6—6 of Fig. 5. Fig. 7 is a detail view of gearing hereinafter more particularly described.

Like characters refer to like parts throughout the several figures.

55 It is not material what is fed by mechanism involving the present invention, al-

though as I have already intimated said mechanism is of peculiar utility when embodied in a paper cup machine, being employed in this case to supply blanks one at 60 a time, from a pile or stack to cup-forming mechanism. The blanks may vary as to shape, although in the present instance they are circular or consist of paper disks. When of this form they are supplied to plaiting 65 mechanism which constitutes the subject matter in part, of a separate copending application filed August 19, 1912, Serial No. 715,790. As a matter of fact I prefer to duplicate the plaiting or other cup-forming 70 mechanisms. From this it will be clear that it is not necessary that the cup should be former by plaiting.

The different parts of the machine may be supported by any suitable framework, that 75 shown being denoted in a general way by 10. The blank support may be of any suitable nature, that shown being denoted by 12 and being disposed as represented, at an upward, forward inclination and being provided with several upstanding rods or stanchions 13, to receive and confine the pile of blanks, there being in the organization illustrated three of such rods, two of which engage the sides of the pile of blanks at 80 substantially diametrically opposite points, while the third one engages the rear of said pile. This practically presents a skeleton carrier for the pile of blanks, open at the forward side, the opening at such point permitting the free removal of the blanks which in the organization shown are positively removed one by one from the stack, at the bottom. The support or shelf 12 as illustrated is approximately rectangular and the 85 forward, upper side of the pile or stack of blanks extends forward beyond or overhangs the front end of said support to facilitate the removal of the blanks which as will herein-after appear are bent downward upon themselves one at a time to initiate the withdrawing or separating movement and to insure the proper folding or flexing of the blanks, the front edge of the support or shelf 12 is shown as beveled on a downward outward 90 angle.

In connection with the blanks there is a positive removing or withdrawing device, and although this may vary in nature, one of pneumatic type satisfactorily answers my 110 requirements. The member shown for this purpose will now be described, being de-

noted in a general way by 14. This blank-withdrawing member includes in its make-up a tubular shaft 15 supported for rocking motion by suitable bearings on the frame-work 10 and having between its ends the crank or forwardly bowed portion 16, provided with an upwardly curved or arcuate hollow or tubular finger 17 adapted to pick the sheets or blanks from the stack in succession. In the present case the axis of motion of said shaft 15 intersects the front edge of the support or shelf 12. It should be stated that accidental bending downward of the stack of blanks where the same over-hangs the front of the support or shaft 12, is prevented in some positive manner, and for this purpose the projection 18 may be provided, this projection engaging under the front portion of the stack for such purpose. This detent 18 depends from the yoke 19, the ends of which are supported in suitable bearings on the framework of the machine.

The blank withdrawing or removing device 14 as will hereinafter appear is intermittently oscillated, the tip of the picking finger 17 being normally free or away from the lowermost blank of the stack. On the advancing movement of the withdrawing member 14 said tip or free end of the finger 17 is brought into contact with the lowermost blank of the pile, and simultaneously the air is exhausted from the said withdrawing device 14 so that the forward portion of the lowermost sheet on the retractive or downward movement of the finger 17 is drawn by suction in a downward direction, said sheet being flexed at the front edge of the shelf or support 12 and being separated from the detent 18. The sheet when the free portion thereof is thus pulled down, is received between a pair of gripper and feed rolls of novel construction and which will be hereinafter more particularly described.

The sides of the framework support the power shaft 20 which may be rotated in any desirable manner, and from which a pump or equivalent apparatus for exhausting the air from the blank withdrawing device 14 may be driven. This pump may be of any suitable character; as a matter of fact any other means may be provided for the same purpose. The pump shown comprises in its make-up the cylinder 21 and the piston 22 therein, the stem of the piston having a fork 23 straddling and guided by the power shaft 20. To reciprocate the piston 22 the cam 24 rotative with the continuously operable power shaft 20, may be provided, said cam having a side groove 25 to receive the stud 26 on the stem of the piston 22, this providing a simple means for reciprocating said piston. It should be noted that the parts are so proportioned that the suction stroke of the piston 22 will commence just about the time the picker finger 17 comes

in contact with the lowermost blank and will continue until the blank operated upon by said picker finger has been grasped by the gripping and feed rolls which I will hereinafter more particularly describe. The pump cylinder 21 is connected by piping as 27 with one end of the shaft 15.

To oscillate the shaft 15 and therefore impart a corresponding movement to the picker finger 17 any suitable means may be provided, although in the present case one stroke is effected by cam means and the opposite by spring means, the cam for this purpose being denoted by 28, being rotative with the power shaft 20, and being adapted to engage against the projection 29 on the crank arm 30 rigid with the inner end of the shaft 15. Encircling the shaft near said end is a coiled spring 31, one end of the spring being connected to the shaft and the other to a fixed pin 32 on the framework 10. The cam 28 acting against the stud or projection 29 tends through the described parts, to impart a downward movement to the crank arm 30 and therefore to the picker finger 17 during which the spring 31 is tensioned, so that when the releasing portion of the cam frees the projection or stud 29, opposite movement of the crank arm and picker finger can be accomplished by the reaction of said spring.

The sheets or blanks when successively pulled down as described are presented to suitable forwarding means which as shown consist of superposed rollers 35 and 36, both of which in the present instance are apertured or slotted between their ends to provide for the swing of the picker finger 17. The apertures of the two rollers can be conveniently secured by making said rollers in sections and the picker finger 17 operates in the said apertures. The lower roller 35 is fixed to the main shaft 20, while the shaft of the upper roller 36, is formed in sections 37 and 37' supported for rotation respectively by the ends of the yoke 19 which effectually maintains said shaft sections in axial alinement. The main shaft 20 has fixed to it the spur gears 38 in mesh with pinions 39 on the shaft sections 37 and 37', this presenting a simple means for simultaneously rotating the two rollers 35 and 36. Said rollers 35 and 36 are shown of different diameters, the upper one 36 being in the present case smaller than the lower, although this is not essential.

The intermediate, slotted or apertured portion of the upper roller 36 is removed as at 40 to produce the web 41 which is of crescent or segmental form in cross section. When the forward portion of the lowermost blank or sheet is pulled downward by the picker finger 17 in the manner already described, its front portion is entered in the cut away portion 40, the front edge thereof

practically traversing the inner face of the segmental web 41. This motion continues until the blank is brought upon the periphery of the lower roller 35, so that when the outer surface of the web 41 or the uncut portion of the roller 36 comes in contact with the sheet of paper on the lower roller 35, the two rollers can seize and wholly remove the sheet from the stack and enter the same into the bight of a second pair of rollers 42 and 43 operable as hereinafter set forth, which advance the same onto a carrier such as that denoted in a general way by 47. One of the spur gears 38 is in mesh with the wide-faced pinion 44 mounted as an idler on the framework and which in turn meshes with the spur gear 45 meshing in turn with the similar gear 46, said gears 45 and 46 being fixed to the shafts of the feed rollers 42 and 43 to simultaneously rotate the same. Said carrier 47 includes in its make-up, companion endless bands or belts 48 which act as one of their functions to simultaneously advance the blanks up to a certain point. Each belt also acts to transfer power as will hereinafter appear. The inner portions of the two belts 48 are fitted around a drum 49 complementary to the pressure drum 50 located directly over the same, the upper drum bearing against the inner portions of the two belts. Fastened to the shaft of the lower drum 49 is a spur gear 49' in mesh with the wide-faced pinion 44 and in mesh with the spur gear 49' is a like spur gear 50' fastened to the shaft of the upper drum 50 and by which the two drums can be rotated in unison.

The belts between their ends are bent downward to provide openings as will hereinafter appear, for the passage of a feed or pusher member which is preferably oscillatory, and as will also hereinafter appear, said belts are extended outwardly at the place where the pusher member operates.

I will describe the mounting of one belt 48 which will apply practically to the other.

The upper run of the belt 48 in the foreground in Fig. 2 extends over the guide sheave 51 and downward around the guide sheave 52 and then upward around the guide sheave 53, the guide sheaves 51 and 53 being virtually horizontally aligned, while the guide sheave 52 is below the two other sheaves, the three being practically triangularly arranged so as to form as it were a triangular opening 48' in which the feed member 54 can operate. The belt 48 after leaving the sheave 53 extends downward around the sheave 55, the axis of which is at right angles to those of the other sheaves being disposed, however, as are the others horizontally. The belt then extends laterally of the machine, and is passed around the sheave 56 of comparatively large diameter and then

again inward around the sheave 57, the two sheaves 56 and 57 being rotative about vertical axes. The sheaves 51 and 52, 53, 55 and 57 are supported by a bracket 58 which may be attached to the framework 10 or supported on a column as 59 extending to the floor, the sheave 56 of large diameter being supported by a side bracket 60.

Associated with each sheave 56 is cup-forming mechanism, although the same is not shown herein. This cup-forming mechanism may be of any suitable character, for example of the kind which form by plaiting, the circular blanks or disks, into cup shape. As already intimated, however, the cup-forming or shaping mechanism constitutes no part of the present invention, for which reason it is not referred to more particularly herein.

The feed or pusher member 54 to which reference has been made as shown is fastened to the rock shaft 61 carried upon the arm 62 surmounting the post or standard 63 on the framework 10. To the outer or forward end of the rock shaft 61 is fastened the rocker 64 to which is jointed the rod 65 adapted to be power-operated in some suitable manner, to oscillate or swing the feed or pusher member 54 which when in its mid position, stands approximately centrally between the feed portions of the two belts 48 and which, as will be clear has a movement alternately through the triangular openings 48' in the two belts 48. The belts 48 jointly advance the blanks or disks up to the feed or pusher member 54 and as the said pusher member oscillates, it pushes the blanks alternately in opposite directions, the first blank operated upon being moved for instance toward one sheave or equivalent support 56 and the ensuing one toward the complementary sheave or support 56, this action being continued as long as the blanks are fed and the machine is in motion.

To guide the blanks onto the respective rotary supports 56, the parallel guide members 66 may be provided, these members being fastened to the stationary shafts of the two pairs of upper guide sheaves 51 and 53 and extending outward therefrom. The outer ends of the guide members 66 extend short of the rotary supports 56.

What I claim is:

1. The combination of a carrying and power transferring device, means for supplying a blank to said carrying and power transferring device to be advanced thereby, a blank support, driven by the carrying and power transferring device, and means for positively removing the blank from the carrying and power transferring device and forwarding it toward said blank support.

2. The combination of a pair of bands, supporting and guiding means for the bands positioned to form in said bands, openings,

means for supplying blanks to said bands to be advanced thereby, and pusher means movable through the openings made by said bands, for removing the blanks from the bands and for pushing the same alternately in different directions.

3. The combination of a drum, a pair of rotary blank supports, bands both of which are passed around the drum and each of 10 which is passed around and drives a blank support, the bands being extended outward between the drum and blank support, means for supplying blanks to the bands, the latter being adapted to jointly advance the blanks, 15 and means for pushing the blanks alternately from the bands approximately at the point where they extend outward and toward said blank supports.

4. The combination of a pair of bands 20 disposed approximately in parallelism for a portion of their lengths and extended outward beyond their parallel relation, means for supporting and guiding said bands, means for supplying blanks to the parallel 25 portions of the bands to be advanced thereby, means for removing the blanks from the bands at substantially the point where their parallel relation terminates and blank supports receiving the outwardly extending portions of the bands, driven by said bands, and adapted to receive said blanks when they 30 are removed from said bands.

5. The combination of a pair of bands disposed approximately in parallelism for 35 a portion of their lengths, and extended outward beyond their parallel relation, means for supporting and guiding said bands, means for supplying blanks to the parallel portion of the bands to be advanced thereby,

and means for removing the blanks from the bands at substantially the point where their parallel relation terminates and for pushing the blanks alternately in opposite directions.

6. The combination of a carrying and power transferring device, means for supplying a blank to said carrying and power transferring device to be advanced thereby, a blank support rotative by said carrying and power transferring device, and means 50 for positively removing the blank from the carrying and power transferring device and forwarding it toward said blank support.

7. The combination of a carrying and power transferring device, means for supplying a blank to said carrying and power transferring device to be advanced thereby, a blank support driven directly by the carrying and power transferring device, and means for positively removing the blank 60 from the carrying and power transferring device and forwarding it toward said blank support.

8. The combination of a blank carrying device, supporting and guiding means for said blank carrying device, positioned to form therein an opening, means for supplying blanks to said device to be advanced thereby, and means movable through said 65 opening for removing the blanks from said device.

In testimony whereof I affix my signature in presence of two witnesses.

WALTER E. CLAUSSEN.
